UNITED STATES PATENT OFFICE.

CHARLES E. MARTIN, OF PAULSBORO, NEW JERSEY, ASSIGNOR TO VACUUM OIL COMPANY, OF NEW YORK, N. Y., A CORPORATION OF NEW YORK.

APPLYING AND SECURING MACHINES FOR CONTAINER CLOSURES.

Application filed February 14, 1927. Serial No. 168,172.

The present invention relates to applying and securing machines for container closures and an object of the invention is to provide a machine which will make it possible to feed closures of irregular shape or form from bulk where they are indiscriminately arranged, to one or more registered positions from which they are moved by one or more expanding tools and secured by such expanding tool or tools to a container or containers. Another object of the invention is to provide a novel means of feeding the irregularly shaped closures from a hopper so that they may travel from the hopper in which they are indiscriminately arranged to definite positions. Still another object of the invention is to provide a novel means of positioning a closure between an applying and securing tool and the support on which the container rests so that the tool may move the closure from the positioning means to the container and secure such closure thereto. A further object of the invention is to provide a novel means for operating the plunger of a closure expanding tool, such means being particularly adapted for use when a plurality of expanding tools are employed. Still another object of the invention is to provide a centering means interposed between a closure expanding tool and the support for a container and adapted to cooperate with a portion of the container upon a relative movement between the expanding tool and the support, so that the container is centered on the support with reference to the expanding tool. A still further object of the invention is to provide a novel feeding means which will shift containers on a support substantially to a centered position with reference to an expanding tool. Another and still further object of the invention is to provide a novel construction in which the containers as they pass to the support effect the operation of the machine to move a container to substantially a centered position beneath a closure expanding tool to effect a relative movement between the container and the expanding tool in order to cause the expanding tool to apply a closure to the container and effect the operation of the expanding tool to interlock the closure with the container.

To these and other ends, the invention consists of certain parts and combinations of parts, all of which will be hereinafter de-

scribed: the novel features being pointed out in the appended claims.

In the drawings:

Fig. 1 is a view in side elevation of a machine constructed in accordance with this invention, the upper part being broken away; 60

Fig. 2 is a view of the opposite sides with the end portions of the feeding and discharge conveyors broken away;

Fig. 3 is a horizontal section through the machine above the conveyor; 65

Fig. 4 is an end view of the machine showing the discharge conveyor in section;

Fig. 5 is a vertical section through the machine;

Fig. 6 is an enlarged fragmentary vertical section through the machine; 70

Fig. 7 is a plan view on a portion of the mechanism for feeding the seals or closures;

Fig. 8 is a fragmentary vertical section through the closure expanding mechanism; 75

Fig. 9 is a section on the line 9—9, Fig. 6;

Fig. 10 is a section on the line 10—10, Fig. 6;

Fig. 11 is a fragmentary view showing the manner in which the closure is expanded 80 into interlocking connection with the container; and

Figs. 12 and 13 are sections on the lines 12—12 and 13—13 respectively Fig. 7.

The present machine is designed for operating upon closures or seals of the type indicated in Figs. 8, 9 and 10 of the drawings where there is employed a cup shaped member 1 having a surrounding outwardly turned flange 2. This closure is introduced 90 into the nozzle 3 or filling spout of a container 4, the nozzle or filling spout having an inwardly turned flange 5, the flange 2 of the closure being brought into engagement with the outer face of the inwardly turned flange 5 and the body of the closure then being expanded at 6, below the flange 5 in order to retain the closure within the spout or filling nozzle of the container 4. 95

In the illustrated embodiment of the invention, the main frame of the machine embodies two uprights 7 and 8. These uprights are connected at their lower portions by angle iron pieces 9 on which a table or plate 10 is supported. The side pieces 7 and 8 are 100 also connected at intermediate portions by horizontal angle iron pieces 11, which support both the feeding and the discharge con- 105

veyor of the machine. In this instance, two longitudinally extending side pieces 12 are supported on these cross pieces 11 and project from opposite sides of the machine. At 5 the intake of the machine, these side pieces 12 are deflected upwardly at 13 so that the intake or feeding conveyor is in a slightly higher plane than the discharge conveyor. These side pieces are held in properly spaced 10 relation by tie rods 14 connecting the side pieces in parallel relation both at the receiving end and the discharge end of the machine. Preferably between these tie rods 14 and 15 are arranged, the rollers being 15 preferably mounted to turn on shafts 16 connecting with the side pieces 12.

Between the two conveyors and in the plane of the main portion of the frame of the machine is a support comprising in this 20 instance a plurality of flat plates 17 with their flat faces vertically arranged each being parallel with the other plates, and the plates being connected by tie rods 18 and being supported upon the cross pieces 11. The 25 plates preferably project on the side of the machine nearest the receiving end toward the feeding conveyor, and the latter has its nearest roller 15 spaced a greater distance from the main portion of the machine than the 30 nearest roller 15 of the discharge conveyor.

It is apparent that the machine may be driven in any suitable manner, but in this instance an electrical motor 19 is supported on the table 10 and has a pinion 20 on the 35 shaft thereof meshing with a gear 21 on the main drive shaft 22 of the machine, said drive shaft being journalled in the side pieces 7 and 8 and having the different mechanism of the machine operated therefrom.

40 The cans to be closed or sealed are preferably arranged in boxes or receptacles 22^a in which they are to be shipped and are moved on the intake conveyor in any suitable manner, in this instance by hand, until 45 they come to rest on the extended portions of the support on which they are positioned when the cans are sealed.

With the end in view of feeding the receptacles 22^a automatically to a substantially 50 centered position where the cans can be effectively sealed or closed, a feeding mechanism may be employed which carries the receptacle 22^a off the extended portion of the support onto that portion directly beneath 55 the sealing or closure applying and securing means to be hereinafter described. This feeding mechanism in this instance comprises two arms 23, secured pivotally to feed rods 28 by heads 24 and extending upwardly from said rods, with their free ends slightly in advance to the extended part of the support. To the end that these arms will not be engaged by the receptacle 22^a in passing from the receiving conveyor to the extended portion of the support, between the 60 65

last roller 15 of the feeding conveyor and the extended portion of the support, and on opposite sides of the arms 23, two pairs of short rollers 25 are mounted, the shafts of these rollers being journalled at their outer ends in the side pieces 12 and at their inner ends in plates 26 which are bolted at 27 to the outer plates 17 of the support. It is thus apparent that the cases or receptacles 22^a which are substantially as wide as the distance between the side plates 12, will pass over the arms 23 without engaging the same and after the last portion of the case or receptacle 22^a passes off the last small roller 25, the case 22^a will drop on the extended portion of the support in advance of the forward ends of the arms 23 so that said arms can be utilized for feeding the cans or receptacles 22^a to that position on the support where the sealing mechanism can operate thereon. 70 75 80 85

With the end in view of operating the arms 23 to feed the cases or receptacles 22^a, the heads 24 may be supported on a slide frame comprising, in this instance, two slide rods 28 arranged in parallel relation and guided in the angle irons 11, their other ends being located on the opposite sides of the machine beneath the discharge conveyor and being connected by a cross piece 29 that has wheels 30 at opposite ends guided on tracks 31 supported at their inner ends by one of the cross pieces 11 and at their outer ends by brackets 32 depending from the sides 12 of the discharge conveyor, these tracks also acting as braces for such discharge conveyor. 90 95 100

The operation of the feeding slide may be effected in any suitable manner. In this instance the cross piece 29 is engaged by the slotted ends of two arms 33 of a yoked lever which has its lower end rigidly secured to a rock shaft 34, this rock shaft also having an arm 35 which has a pitman 36 pivoted to it at 37. The other end of this pitman carries a guide yoke 38 and a laterally extending roller 39 which operates in a cam groove 40 formed in one face of a cam 41 keyed to a shaft 42 which is journalled in the side frames 7 and 8 in parallel relation to the drive shaft 22, and is geared to said drive shaft through a pinion 43 on the drive shaft meshing with a pinion 44 mounted to turn loosely on the shaft 42, and adapted to be connected to the latter through a one-revolution clutch 45 of any known construction. The operation of this clutch is such that, when once thrown into connection between the gear 44 and the shaft 42, it maintains such connection until the gear 44 has made one complete revolution and then affects the disconnection between the gear 44 and the shaft 42. 105 110 115

With each operation of the one-revolution clutch 45, the feeding slide will be moved first in one direction to shift a case 22 from the extended portion of the support to a substantially centered position beneath the 120 125 130

sealing or closure applying and securing mechanism, at the same time displacing the case containing the containers previously sealed onto the discharge conveyor, and that, 5 thereafter, the feeding slide will carry the engaging portions 23 of the feeder back to their original positions illustrated in Fig. 5, so that another case may be moved by the feeding slide to the sealing position.

10 For effecting the operation of the one-revolution clutch any suitable means may be employed. In this instance, a tripping mechanism is brought into operation immediately that the case 22^a is received upon the extended portion of the support. This is effected, 15 in this instance, through a tripping device in the form of a bell crank lever having one arm 46 normally held slightly above the plane of the extended portion of the support 20 and below the plane of the receiving conveyor at a point between the receiving conveyor and the extended portion of the support so that as the case 22 drops from the receiving conveyor onto the support it engages 25 this arm and moves the other arm 47 against the action of a spring 48 to shift the link 49 which connects with the one-revolution clutch 45 and effects the operation of the latter, the spring 48 returning the tripping mechanism to normal position after the feeding mechanism has shifted the case 22^a out 30 of engagement with the arm 46 of the tripping device.

The sealing or closure applying and securing mechanism, in this instance, is designed to seal or close at one time ten cans in each case and to this end has ten sealing or closure applying and securing devices. These devices, in this instance, are mounted on a 35 vertically movable head or cross piece 50 which has guides 51 at opposite ends guided on the opposed faces of the uprights 7 and 8 and having rods 52 depending therefrom and carrying guide yokes 53 at their lower 40 ends guided upon and straddling the shaft 42 hereinbefore mentioned. This vertically movable frame which carries the sealing or closure applying and securing devices is 45 preferably operated through rollers 54 on the yokes 53 operating in the cam grooves 55 formed on the outer faces of cams 56 mounted on the shaft 42. It is thus apparent that each revolution of the shaft 42 through the one-revolution clutch 45 effects 50 the lowering and raising of the frame which carries the sealing or closure applying and securing devices. Of course, the lowering of this frame is so timed that it takes place 55 after a case 22 with the cans or containers 60 therein has been removed to a position beneath the head 50 by the case feeding mechanism.

In order to insure that the ten cans will 65 have their spouts properly positioned beneath the sealing devices there is provided

a centering or positioning means. In this instance this centering or positioning means is in the form of a plate 57 which is yieldingly carried by the head 50. This plate has a number of openings 58 therein corresponding to the number of cans or containers to be sealed and having a diameter slightly larger than the exterior diameter of the spouts 3 of the containers, the openings being spaced apart a distance substantially equal to the 70 distance between the spouts of ten cans or containers when arranged within the case 22 in the manner shown in the drawings. The plate 57 has its underside provided with tapered portions 59, one leading to each 75 opening 58 so that after the centering means moves toward the ten spouts within a case 22, these tapered portions will cooperate with the ends of the spouts and direct them to the openings 58, the spouts being passed entirely through the centering openings so that their upper ends are arranged for operation upon by the sealing or closure applying and securing devices. Preferably, the centering 80 means is yieldingly supported from the head 50 and moves in advance of the latter to engage and position the containers before the sealing or closure applying and securing devices are brought into operation. In this instance, the centering plate 57 carries guide 85 rods 60 which are guided in the head 50 and are surrounded by helical springs 61 arranged between the head and the plate 57.

Each sealing or closure applying and securing device embodies, in this instance, a tubular expanding tool 62 having its upper end passed through the head 50 and held thereto by a nut 63 engaging the top of the head, a shoulder 64 on the tubular expanding tool below the head cooperating with the underside of the latter. This tubular expanding tool is slotted at 65 to provide for the expansion of the tool and the lower end of the tool is formed with a shoulder 66 for cooperating with the flange 2 of the sealing 100 closure and also has below said shoulder 66, an annular rib 67 arranged in spaced relation to the shoulder to provide between the rib and the shoulder an annular groove 6. Each expanding tool may be magnetized so as to hold the sealing closure thereto or the annular rib 67 may have such a diameter that it will tightly or frictionally fit the interior walls of the sealing closure before the latter is expanded or while it is in the condition shown in Figs. 8, 9 and 10. After the sealing closure is fitted to the end of an expanding tool and the head 50 carries the closure into a spout of a can or container, the tool is expanded so as to cause the closure to 105 be bent or distorted as shown in Fig. 11 to interlock with the flange 5 of the spout or container.

The expansion of each tool may be effected in any suitable manner. In this instance 110

within the hollow expanding tool 62 is arranged a plunger 68 the lower end of which is bevelled at 69 to cooperate with a tapered internal bore or surface 70 at the lower end 5 of the expanding tool 62. Movement of this plunger 68 is so timed with relation to the other mechanisms of the machine that it operates after the expanding tool has carried the sealing closure into the spout of the container. This movement is effected in any suitable manner. In this instance a screw 70^a is adjustable in the upper end of this plunger 68 and has a head 71 provided with a pocket 72 in which is received the 10 free end of an operating dog 73 which is pivoted at 74 to an arm 75 extending laterally from a shaft 76. Two of these shafts 76 are preferably provided and each, in this instance, has five arms with five operating 15 dogs 73 pivoted thereto so that through the two shafts all of the plungers 68 may be operated. The two shafts are preferably geared together through gear segments 77 while one of them is provided with an arm 20 78 which at 79 is pivotally connected to a plunger 80, this plunger being vertically arranged and extending downwardly through a guide 81 on the side of one of the side rails 12, its lower end being positioned above a 25 tappet lever 82 which is pivoted at 83 to the frame of the machine and lies above an operating cam 84 arranged on the shaft 42, this operating cam having a projection 85 which is so positioned that it operates the 30 tappet lever 83 to cause the latter to move the lower end of the plungers 80 after expanding tools have inserted sealing closures in the nozzles of the cans or containers on the support, thereby causing both of the 35 shafts 76 to be rocked and the operating dogs 73 to depress the plungers 68 to expand the expanding tools. A spring 86 anchored at one end to the frame of the machine and secured at the other end to the pivot 79 of the plunger tends normally to hold the 40 plunger 80 in its lower position on the head 50 against an adjustable stop 80^a. It is apparent that the operating dogs with the arms 75 form toggles which are straightened when 45 the tappet lever 82 moves the plunger upwardly and break under the action of the spring 86 when the head 50 carries the plunger 80 upwardly with it after the sealing closures have been interlocked with the 50 nozzles of the cans. The adjustable screws 70^a make it possible to vary the movement of the plungers 68 under the action of the aforesaid toggles so that the amount of expansion of the expanding tool may be controlled. These screws also permit the adjustment of the friction of the expanding tools on the sealing closures so that the expanding or sealing tools may be utilized for holding the sealing closures to them while 55 they are moving toward the nozzles of the

cans or containers. The expanding tools may also be magnetized to still further insure the holding of the sealing closure thereto.

Any suitable means may be employed for feeding the sealing closures to registered positions where they may be engaged by the expanding tools. In this instance, the sealing closures are dumped indiscriminately into a hopper 87 arranged above the movable head 50 and separated therefrom by a partition 88 having curved portions on opposite sides of the head 50. To one side of each of these curved portions the reversely inclined bottom 89 of the hopper is formed with a plurality of parallel grooves 90 which have a cross section similar to a diametric cross section of a sealing closure 1 so that sealing closures may be received in these grooves in an upright position in which case no portion thereof will lie above the surface of the bottom 89. If, however, the position of a sealing closure is irregular within a groove, then a portion thereof will project above the bottom surface. In this instance, ten of these grooves are provided, five on each side of the sealing mechanism and each inclining downwardly toward the applying and securing mechanism. In order that only those sealing closures which are properly positioned within the groove may pass downwardly by gravity within the grooves, there are provided two wipers each of which wipes over one portion of the bottom 89 to displace any sealing closures which project from the grooves above the bottom 89. In this instance, each of these wiping devices embodies a drum 91 having a shaft 92 and provided with tangentially extending flexible wiper plates 93. The shafts 92 of these two wipers each has a gear 94 thereon on the outside of the hopper and about these gears is passed a sprocket chain 95 which also passes about a sprocket wheel 96 on the shaft 42. This sprocket chain also passes about an idler pulley 97 which is adjustably supported by a bracket 98 in any suitable manner in order to take up slack in the chain 95. It is apparent that with each rotation of the shaft 42, the wipers will be operated to wipe over the bottom surface of the hopper in order to displace any sealing closures improperly placed in the grooves 90.

From the grooves 90 channel members 99 lead downwardly to two cross heads 100 which are rigidly supported on side plates 7 and 8. These channel members (see Fig. 10) are so formed that they each feed one at a time the sealing closures to a feeding plate 101. This feeding plate is guided at 102 on the two cross pieces 100 between the two banks of guides 99 of five each. It is provided with openings 103 in line with guides 99 to receive sealing closures. The feeding plate 101 is then moved laterally so openings 103

- 103 come directly beneath and aligned with the expander tools so that the latter in their first downward movement will engage with the sealing closures. The sealing closures 5 are picked up by the expanders and held to same by friction or magnetism, this condition being continued while the closures are being carried to and introduced into the spouts of the containers, and are then raised 10 to the top position of expander head to allow the feeding plate 101 to slide or return to its original position so holes 103 are positioned directly beneath and aligned with the expander tools. The diameter of the 15 holes 103 are larger than the flange 2 of the sealing closure, and as a consequence, the sealing closures will pass through the holes 103 on the second downward movement of the expander tools and be introduced into 20 the spout 3 of the cans or containers 4, the spouts of the latter having previously been centered through the engagement of the centering plate 57, moving in advance of the expanding tools, and this connection is maintained 25 until the expanding tool is operated to interlock the closure to the spout of the container. After this interlocking the weight of the container acting on the sealing closure holds the latter so that the expanding tool 30 after being contracted due to the movement of the plunger 68 upwardly, may pass out of connection with the closure. The feed plate 101 may be moved in any suitable manner, in this instance, a lever 104 pivoted at 35 105 to the frame of the lever has a slidable connection 106 with an extension 107 on said plate, this lever being operated through a cam 108 arranged on the shaft 42.
- The operation of the invention will be understood from the foregoing, but it may be summarized as follows:
- The sealing closures are dumped indiscriminately into the hopper 87 and pass from the latter through the grooves 90 in 45 the bottom of the hopper to the channels 99, which conduct them to the feeding plate 101. The expander head descends and picks up the sealing closures and rises to allow feeding plate to move laterally to bring holes 103 50 in alignment with expander tools 62, which will enable the expander tools to pass through holes 103 and introduce sealing closures into spouts of cans or containers, the spouts having been previously centered 55 through the engagement of the centering plate 57, moving in advance of the expander tools. Thereafter the expanding tools are expanded through plungers 68 and are then contracted and withdrawn from the closures. 60 The cases 22^a carrying a number of cans or containers are moved by gravity down the intake feeding conveyor or runway, and drop from the latter on to the projected portion of the support beneath the expander tools. As each case 22^a drops from the feed- 65
- ing or intake conveyor to the support, it engages the trip 46 and thus establishes connection between the drive shaft 42 and the feeding mechanism for the case, causing the arms 23 to engage that case, cooperating 70 with a tripping mechanism and shift such case so its containers are substantially in centered position beneath the expanding tools. The case moved by the feeding mechanism shifts in the case of containers, previously sealed or closed, onto the discharge conveyor from the support beneath the expander tools. About the time a case 22^a is shifted, the feed plate 101 is shifted to align 75 the closures in the feed plate with the expander tools, permitting the latter to operate as hereinbefore mentioned. All mechanisms, however, are controlled through the one-revolution clutch by means of the trip 46 so the machine operates through the dropping of a case 22^a thereon from the intake or feeding conveyor.
- What I claim as my invention and desire to secure by Letters Patent is:
1. A machine of the class described comprising a support for a container, a conveyor leading to said support, a feeder for moving a container on the support to a registered position thereon, a drive shaft having driving connection with said feeder provided with a clutch in said driving connection, and a trip arranged to be engaged by a container as it moves onto the support from the conveyor to establish driving connection between the driving shaft and the feeder, causing the latter to move the container on the support to the registered position. 90
  2. In a machine of the class described, the combination with a support for a container, of a conveyor for conveying containers to the support having its supporting surface arranged in a higher horizontal plane than the support, a reciprocating feeder having a portion for engaging the containers on the support to move the latter thereon, said portion, when in its initial position, lying in a horizontal plane above the support, in advance of the rear end of the conveyor and below the supporting plane thereof, so that the container may travel on the conveyor without being engaged by such portion, and may drop onto the support in front of the engaging portion so that the container is in position in advance of the engaging portion to be moved by the latter. 95
  3. In a machine of the class described, the combination with a support for a container, of a conveyor for conveying containers to the support arranged in a higher horizontal plane than the support, a feeder slidably mounted below the support and having an engaging portion for engaging the container on the support to move the latter thereon, said portion lying when in its initial position in a plane above the support and in ad- 100
  - 110
  - 115
  - 120
  - 125
  - 130

vance of the rear end of the conveyor and below the supporting plane thereof.

4. In a machine of the class described, the combination of a support for the container, 5 of a roller conveyor having at its supporting surface arranged in a higher horizontal plane than the support and having at its end adjacent the support small rollers spaced apart, and a reciprocatory feeder having a 10 portion for engaging the containers on the support to move the latter thereon, said portion when in its initial position lying in a horizontal plane above the support and below the supporting plane of the roller conveyor and also in the space between the small 15 rollers.

5. A machine of the class described comprising a support for a container, a conveyor or leading to said support and having its 20 supporting surface in a horizontal plane above the supporting surface of the support so that a container moving from the conveyor to the support must drop on such movement, a feeding means for moving the 25 container on the support, driving mechanism for said feeding means, and a trip controlling such driving means and arranged in a position to be engaged by a container as the latter drops from the conveyor to the 30 support.

6. The combination with a support for a plurality of containers, of a plurality of closure applying and securing devices movable toward and from said containers on the support, and a resiliently supported plate movable toward the support with said closure applying and securing devices in advance of the latter but relatively yieldable thereto, 35 said plate having a plurality of openings 40 through which portions of the containers on the support are adapted to be passed in order to be centered with reference to said closures applying and securing devices.

7. The combination with an expanding 45 head and an operating plunger for the head, movable in the latter, of a screw adjustably connected with said plunger, a shaft, means for oscillating the shaft, an arm carried by the shaft, and an operating pawl pivoted 50 to the arm and engaging said screw.

8. The combination with a support for a container, of a head movable toward and from said support, mechanism for effecting such movement of said head, an expanding 55 tool carried by the head, a plunger for operating said expanding tool, mechanism operating with the head moving mechanism, and mechanism for operating the plunger embodying two parts, one of which is operated 60 by the mechanism which moves the head, and the other of which is carried by the head and is moved into and out of connection with the first mentioned part of said mechanism when the head is moved toward and 65 from the support for the container.

9. The combination with a container support, and a head arranged above said container support, and movable toward and from the latter, of a shaft arranged under said container, driving connection between 70 said shaft and the head for moving the latter toward and from the container support, a cam arranged on said shaft, a tappet member operated by said cam, an expanding tool carried by said head toward and from 75 the container on the support, and means for operating said expanding tool movable with the head toward and from the tappet member so that it may be operated by the latter when the expanding tool is in a position to 80 interlock the closure with the container on the support.

10. The combination with a support for a container, an expanding tool, means for effecting the movement between the expanding 85 tool and the support for bringing the tool into cooperation with the container on the support, and a plunger for expanding said tool, of mechanism for operating said plunger embodying movable parts carried 90 with the expanding tool and movable parts carried with the support, the movable parts carried with the expanding tool and those carried with the support being out of connection when the support and the expanding 95 tool are separated and being in connection when the expanding tool is in cooperation with the container on the support.

11. A feeding hopper having an inclined bottom wall formed with a groove shaped 100 to conform to the article to be fed, and a wiper operable over said bottom wall in a direction opposite to the direction in which the articles travel down the inclined groove so as to wipe from the groove any articles 105 improperly positioned therein.

12. A feeding hopper having an inclined bottom wall provided with a groove shaped 110 to conform to the article to be fed from the hopper, through which the articles travel from the hopper in a definite position, and a rotary wiper having flexible plates movable over the groove in the bottom of the hopper in a direction opposite to that in which the articles travel down the groove.

13. The combination with a support for a container, and a closure expanding tool movable in a straight line toward and from the container support, of a feeding member having an opening through which the expanding tool may be passed, and movable transversely of the line of movement of said expanding tool to bring the opening therein into and out of alignment with the line of movement of the expanding tool, and means for feeding a closure to the opening of the feeding member when said opening is out of line with the expanding tool in order that the closure can be carried by the said member into alignment with the expanding tool 120 125 130

so that the latter may engage the closure to carry the same towards the container on the support, and means for operating the expanding tool to interlock such closure with the container.

14. The combination with a support for a container and a closure expanding tool movable in a straight line toward and from the container support, of a centering member having an opening through which a portion of a container on the support may be passed for the purpose of centering the container portion on the support with reference to said expanding tool, said centering member being resiliently supported and moved with but in advance of the expanding tool so that the container portion is centered before the tool cooperates therewith, and a feeding element having an opening therein over which the closure is adapted to be supported and through which the closure is forced by the expanding tool in order to carry said closure into cooperation with the container portion centered by the centering device, said feeding member being movable transversely in the line of the movement of the closure expanding tool so that it may receive a closure in its opening while the latter is out of line with the expanding tool.

15. The combination with a support for a container and a closure expanding tool movable in a straight line toward and from the container support, of a centering member

having an opening through which a portion of a container on the support may be passed for the purpose of centering the container portion on the support with reference to said expanding tool, said centering member being resiliently supported and moved with but in advance of the expanding tool so that the container portion is centered before the tool cooperates therewith, and a feeding element having an opening therein over which the closure is adapted to be supported and through which the closure is forced by the expanding tool in order to carry said closure into cooperation with the container portion centered by the centering device, said feeding member being movable transversely in the line of the movement of the closure expanding tool so that it may receive a closure in its opening while the latter is out of line with the expanding tool.
